[57] CLAIM

The ornamental design for a compartmentalized storage unit, as shown and described.

DESCRIPTION

FIG. 1 is a reduced perspective view of a compartmentalized storage unit showing my new design;

FIG. 2 is a top plan view, the bottom being a mirror image thereof;

FIG. 3 is a front elevational view thereof;

FIG. 4 is a side elevational view taken from the left of FIG. 3, the side opposite being a mirror image thereof.
